(57) **CLAIM**

The ornamental design for a pool table and aquarium combination, as shown and described.

DESCRIPTION

FIG. 1 is a perspective view of a pool table and aquarium combination, showing my new design;

FIG. 2 is a side elevational view thereof, the opposite side being a mirror image;

FIG. 3 is an end view thereof, the opposite side being a mirror image; and,

FIG. 4 is a top plan view thereof.

The bottom view is specifically disclaimed.
